(No Model.)

A. VESTER.

BRACELET.

No. 253,243.

Patented Feb. 7, 1882.

WITNESSES.

Welcome A Greene
John T Blodgett

INVENTOR.

Adolph Vester
By O. Chapman
his Atty.

UNITED STATES PATENT OFFICE.

ADOLPH VESTER, OF PROVIDENCE, RHODE ISLAND.

BRACELET.

SPECIFICATION forming part of Letters Patent No. 253,243, dated February 7, 1882.

Application filed October 15, 1881. (No model.)

To all whom it may concern:

Be it known that I, ADOLPH VESTER, a subject of the Emperor of Germany, residing at Providence, in the county of Providence and State of Rhode Island, have invented a new and useful Improvement in Bracelets, of which the following is a specification.

My improvement consists of a bracelet so constructed that it shall be capable of adjustment in fixed sizes to fit a larger or smaller arm without producing a constriction upon the same, as is done by elastic bracelets.

My invention may be carried out by means of a box containing a clasp constructed with plates having teeth which lock into the hollowed ends of the bracelet by catching over corresponding lips in the bracelet end, and make the bracelet larger or smaller, according to the number of teeth passed into the bracelet, as is shown in the accompanying drawings, in which—

Figure 1 represents a bracelet embracing my invention. Fig. 2 represents the ends of bracelet, the box, and locking device, by means of which the different sizes are obtained, the upper portion of the parts shown being removed to show more clearly the internal construction. Fig. 3 is a representation of my invention, showing in whole and broken lines different sizes in the same bracelet resulting from the construction of the locking devices, and also showing the bracelet open. Fig. 4 is a longitudinal section through the box and ends of the bracelet, presenting a side view in section.

Similar letters refer to similar parts throughout the several views.

A A are the plates, with the teeth B B. C C are the lips on the inside of the hollow ends D D of the bracelet. E E are posts, fitting through holes F F of the shell I of the box of the bracelet. These posts are made hollow, closed at the outer ends, and inside of them slides a rod, K, which serves as a guide and support to the spiral spring H, though any convenient form of spring may be used.

The action of the device is as follows: If the bracelet be open, to close it the ends are brought together, and the outer teeth, B B, slide over the lips C C, when the action of the spiral spring H throws the plates A A back,

so that the lips C C are caught between the first and second set of teeth.

If it be desired to make the bracelet smaller, by pressing upon the posts E E the plates A A are brought nearer together, leaving room between the ends of the second set of teeth, B B, and the shell or side of the box I for the lips C C to pass over and beyond said second set of teeth, when, upon releasing the spring, the lips C C lock between said second set of teeth and the posts E E. To open the bracelet, a pressure on the posts E E leaves the way clear to withdraw the end of the bracelet entirely from the box.

If it is desired that only one end of the bracelet can be withdrawn from the box, the plates A A may be bent, and the length of the outer teeth and lips increased on one side, (as shown in Fig. 2, on the right-hand side,) so that when the plates are in actual contact there will not be sufficient room between the outer teeth and the side of the box for the lips C C to pass, thus keeping one end of the bracelet permanently in the box.

In Fig. 2 the device is represented with the bracelet held by the outer set of teeth, while broken lines show the action of the device on the inner set.

In Fig. 3 the broken lines show the result on the size of bracelet when the lips are caught over the outer set of teeth, and the solid lines the result of catching them over the inner set. The number and range of teeth are not limited.

In the accompanying illustrations there are two plates in the clasp, which plates are received into the hollow ends of the bracelet, and the teeth on the plates interlock with lips at the end of the bracelet; but the bracelet may be made with but one plate armed with teeth, and they made to lock into any side of the bracelet, either over a lip or into a socket.

Having thus described my invention, I claim and desire to secure by Letters Patent—

1. A bracelet with its two ends clasped into a box, and adjustably held therein by means of a spring-clasp located in said box and interlocking with the ends of the bracelet at different fixed points, enabling the bracelet to be adjusted to different sizes, substantially as herein described.

2. A bracelet with its two ends fitting into

a box, and adjustably held there at certain points by a spring-clasp interlocking with the ends of the bracelet, as herein described, and with posts connected and arranged, as herein described, to govern the action of said spring-clasp, substantially as and for the purposes herein described.

3. A bracelet-clasp consisting of a box con-

taining a spring, H, plates A, teeth B, posts E, and rod K, arranged to adjustably connect to with and hold the ends of the bracelet, substantially as herein set forth.

ADOLPH VESTER.

Witnesses:

WELCOME A. GREENE,

JOHN T. BLODGETT.
